Primary Examiner — Zenia Bennett*(74) Attorney, Agent, or Firm* — Scott T. Griggs; Griggs Bergen LLP(57) **CLAIM**

The ornamental design for a buoyancy device, as shown and described.

DESCRIPTION

FIG. 1 is a front perspective view of a buoyancy device having left-right, top-bottom, and front-rear symmetry;

FIG. 2 is a top plan view of the buoyancy device of FIG. 1; and,

FIG. 3 is a front elevation view of the buoyancy device of FIG. 1.
